(57) **CLAIM**

The ornamental design for a light for a loading dock, as shown and described.

DESCRIPTION

FIG. 1 is a front perspective view of a light for a loading dock showing our new design;

FIG. 2 is a front view thereof;

FIG. 3 is a back view thereof; and,

FIG. 4 is a top view thereof.

Bottom, left-side, and right-side views thereof are each the same as the top view in FIG. 4.

The portions of the images shown with dash-dash lines depict of the light for the loading dock that form no part of the claimed design.

1 Claim, 4 Drawing Sheets
